COMBINED JEWELRY AND MONEY HOLDING DEVICE

Robert Lee Smith, Los Angeles, Calif.

Application May 3, 1954, Serial No. 30,307

Term of patent 7 years

(Cl. D86—9)

Fig. 1.

Fig. 3.

Fig. 2.

To all whom it may concern:

Be it known that I, Robert Lee Smith, a citizen of the United States and resident of Los Angeles, in the county of Los Angeles and State of California, have invented a new, original, and ornamental Design for a Combined Jewelry and Money Holding Device, of which the following is a specification, reference being had to the accompanying drawing, forming a part thereof.

Figure 1 is a front perspective view of a combined jewelry and money holding device showing my new design;

Figure 2 is a rear perspective view; and

Figure 3 is a view partly in elevation and partly in section.

The bottom of the combined jewelry and money holding device is plain.

I claim:

The ornamental design for a combined jewelry and money holding device, as shown and described.
